UNITED STATES PATENT OFFICE.

HENRY TIBBE, OF WASHINGTON, MISSOURI.

DESIGN FOR A SMOKING-PIPE.

SPECIFICATION forming part of Design No. 13,990, dated June 19, 1883.

Application filed April 17, 1883. Term of patent 14 years.

To all whom it may concern:

Be it known that I, HENRY TIBBE, a citizen of the United States, residing at Washington, in the county of Franklin and State of Missouri, have invented and produced a new and original Design for Smoking-Pipes, of which the following is a specification, reference being had to the accompanying drawing, forming a part thereof.

10 My invention consists of the new design for a smoking-pipe, which I will now proceed to describe.

Referring to the drawing, in which the figure is a side view of the pipe, A represents the bowl, and B B' the stem. The bowl A is of a general conical shape, with its smaller end at the bottom. The stem B B' is made with a large portion, B, having ornamental transverse beads and curves, and a small portion, B', 20 which is smooth throughout its length, and curved to form a mouth-piece. The bowl A is fixed to the larger portion, B, of the stem at a point between the ends of the same and at an angle of about forty-five degrees. A necessary

feature of the design is also the peculiar superficial finish or appearance of the exterior of the bowl and larger stem-section, B, both of which have numerous small elongated indentations or pits upon their surfaces, which pits or indentations have their long axes transversely 25 to the longitudinal axes of the parts A, B, giving the appearance of corn-cob sections.

What I claim is—

The design for a smoking-pipe, consisting of the conical bowl A, straight and large stem-section B, having transverse heads and curves, and connected to the bowl at an angle, as described, between its ends, and the smooth stem-section B', of reduced diameter, curved to form a mouth-piece, the bowl A and section B' being provided with numerous superficial indentations or pits, whose greatest length is transverse to the longitudinal axes of the bowl and stem, as shown and described.

HENRY TIBBE.
